D. W. BLANC

RADIATOR CAP LOCK

Filed Aug. 31, 1922

UNITED STATES PATENT OFFICE.

DAVID W. BLANC, OF CHICAGO, ILLINOIS, ASSIGNOR, BY MESNE ASSIGNMENTS, TO THE KINGSLEY-MILLER COMPANY, OF CHICAGO, ILLINOIS, A CORPORATION OF ILLINOIS.

RADIATOR-CAP LOCK.

Application filed August 31, 1922. Serial No. 585,496.

My invention relates to improvements in radiator cap locks, and it consists in the combinations, constructions, and arrangements herein described and claimed.

5 An object of my invention is to provide a radiator cap which may be permanently locked to a radiator and which is provided with a hinged cover, whereby access to the interior of the radiator may be attained.

10 A further object of my invention is to provide a device of the character described which has novel means for locking the cap in a predetermined position, whereby the cap is facing forward with respect to the car

15 when it is locked in position.

A further object of my invention is to provide a device of the character described which makes use of a monogram plate, the locking means of the cap being fashioned so as to permit the monogram plate to be disposed in the front of the car when the cap is locked.

20 A further object of my invention is to provide a device of the character described which has novel means for locking the motometer against theft.

25 A further object of my invention is to provide a device of the character described in which the cover of the cap may be opened without the necessity of unfastening locking bolts or the like.

30 A further object of my invention is to provide a device of the character described which has novel means for preventing the water from over-flowing through the cap.

35 A further object of my invention is to provide a device of the character described which is simple in construction, and which is durable and efficient for the purpose intended.

40 A further object of my invention is to provide a device of the character described which has means whereby the cap may be disposed on any radiator.

45 Other objects and advantages will appear in the following specification, and the novel features of the invention will be particularly pointed out in the appended claims.

50 My invention is illustrated in the accompanying drawings, forming part of this application, in which

Figure 1 is a top plan view of the device,

Figure 2 is a vertical section through the device, the motometer being shown in elevation,

55

Figure 3 is a front elevation of a portion of the device, and

Figure 4 is a section along the line 4—4 of Figure 2.

In carrying out my invention, I provide 60 an adapter 1 which is adapted to be disposed over a radiator inlet pipe 2. The adapter is made of various sizes so as to fit the inlet pipes of the various makes of radiators. The outer surface of the adapter, however, 65 is made the same in all cases so as to readily fit the cap 3. In other words, the adapter is provided so as to make a standard size cap fit the inlet pipes of any type of radiator. In the present instance, the adapter 70 is provided with threads 4 in its interior surface which are adapted to receive the threads of the inlet pipe 2. The adapter is securely locked in place when screwed on to the inlet pipe 2 by means of the set 75 screw 5.

It will be noted from Figure 4 that the adapter has a shoulder 6 which is provided with a plurality of vertical recesses 7 in its upper surface. These recesses are 80 adapted to receive a pin 8 which is disposed in a recess 9 of the cap 3. In disposing the adapter on the pipe 2, the adapter is screwed on tightly to the pipe so as to dispose one of the openings 7 in front of the radiator. 85 The pin 8 is carried by the cap 3 and is disposed adjacent to the monogram plate 10. When the cap 3 is disposed over the adapter 1, the cap is rotated until the monogram plate 10 is facing forward with respect to the car. The person assembling the cap to the adapter then knows that the pin 8 is directly above the recess 7 which has been disposed in the front of the car. A screw 11 locks the pin 8 in the recess 9 and it will be 90 obvious that by merely unscrewing the screw 11, the pin 8 will drop into the recess 7, whereby the cap 3 will be locked against rotation with respect to the adapter 1. Furthermore, it will be noted that the cap 3 95 covers the set screw 5, thus preventing access to the set screw. 100

I also provide novel means for preventing the cap 3 from being moved upwardly with

respect to the adapter 1 when once the cap has been assembled to the adapter. As clearly shown in Figures 2 and 3, the cap has an annular groove 12 therein which is 5 adapted to receive pins 13, the pins being carried by the adapter 1. Slots 14 communicate with the groove 12 and permit the pins 13 to be received within the groove 12. In assembling the cap to the adapter, the 10 pins 13 are alined with the slots 14, whereupon the cap may be moved downwardly so as to cause the groove 12 to receive the pins. The cap may now be rotated so as to bring the monogram plate 10 into the desired position. The cap cannot be removed from the adapter 1 until the pins 13 are again alined with the slots 14. This movement is prevented by the pin 8 which is received within the recess 7. The set screw 5 and the pins 20 8 and 13 provide a novel means for securely locking the cap 3 to the pipe 2 and preventing the cap from being removed from the pipe.

The cap 3 has a hinged cover 15 which is 25 pivotally secured to the cap at 16, and which carries a tongue 17 (see Figure 1) that is adapted to be received within a recess 18. The recess 18 is in back of the plate 10 and has spherical-shaped depressions 19 therein which are adapted to receive balls 20. The balls 20 are slidably disposed within a bore 21, and are yieldingly kept in extended position by means of the coil spring 22. From this construction, it will be noted that the 35 cover 15 is yieldingly locked in place to the cap 3 when the balls 20 are received within the depressions 19. The cover can be readily opened by merely grasping the motometer 23 which is carried by the cover 15 and moving the latter backwardly about the pivot 16. This movement causes the balls 20 to move 40 inwardly against the tension of the spring 22 so as to release the tongue 17 from the recess 18.

The motometer 23 is also provided with a 45 novel locking means, whereby theft thereof is prevented. The shank 24 of the motometer extends through an opening 25 in the cover 15 and is locked in place by lock 50 nuts 26. The cover 15 has a recess 27 which receives the nuts 26. Access to the nuts 26 is prevented by means of a metal plate 28 which is disposed in an annular groove 29. It will be noted that the plate 28 has an 55 opening 30 therein, through which the shank 24 extends. One wall of the groove 29 is horizontal and provides a stop for the plate 28, while the other wall is substantially vertical, but is also slightly conical-shaped or 60 undercut as is clearly shown in Figure 2. The plate 28, before being disposed within the groove 29, is slightly bowl-shaped so as to permit the plate to be readily disposed within the groove. A nut 31 disposed on the 65 shank 24 is now screwed up so as to move

the plate 28 into engagement with the conical-shaped wall of the groove 29. By tightening the nut 31, the plate 28 is flattened out so as to cause it to be forced into the corner made by the walls of the groove 70 29. When the plate is once forced into this position, it cannot be removed, since the diameter of the plate is greater than the diameter of the entrance of the groove 29. Even though the nut 31 is removed from 75 the shank 24, the plate 28 will stay in the position shown in Figure 2, whereby access to the nuts 26 is prevented.

The upper end of the adapter 1 is flush with a shoulder 32 of the cap 3. A gasket 80 33 is disposed over the shoulder 32 and the top of the adapter 1. The gasket is also adapted to hold a strainer 34 in place, the strainer having a rim 35 which is disposed between the adapter and the gasket. The 85 gasket 33 is made of a resilient material and is adapted to bear against the underside of the cover 15 when the latter is in closed position. In this manner, the gasket is firmly seated upon the shoulder 32 and the 90 top of the adapter 1, whereby it prevents water from flowing between the cap and the adapter.

From the foregoing description of the 95 various parts of the device, the operation thereof may be readily understood. In securing the cap to the pipe 2, the adapter is first disposed on the pipe and is locked in place by the set screw 5 so that one of the openings 7 is disposed in the front of the 100 car. As heretofore stated, the adapter has its inner bore of the required diameter so as to fit the special inlet pipe 2 to which the cap is to be secured. The cap 3 is now disposed over the adapter and is locked in place 105 by means of the pins 13 and the pin 8. The cap also covers the set screw 5 so as to prevent the removal of the set screw. It is obvious that the pin 8 cannot be removed from the recess 7 unless the entire car or the radiator is tipped over. In this manner, the 110 cap is theft proof and is securely locked in place when once secured to the car. The plate 28 also provides a novel means for preventing the theft of the motometer 23. 115 The cover 15 is readily opened without the necessity of first unfastening the bolts or screws. The cover can be opened by merely swinging the motometer 23 backwardly about the pivots 16, thereupon the balls 120 20 release the tongue 17 from the recess 18 in the manner heretofore described. The gasket 33 provides a resilient seat to the cover 15 and also prevents the leakage of water 125 between the cap and the adapter.

It is obvious that any design or signature may be placed on the monogram plate 10. As heretofore stated, the plate 10 is moved so as to be viewed from the front of the car before the cap 3 is locked to the adapter. 130

The device makes a pleasing appearance to the eye and is durable and efficient for the purpose intended. It is obvious that it can be manufactured at relatively slight expense and can be readily secured to all types of cars.

I claim:

1. A device of the type described comprising an adapter having a plurality of recesses 10 therein, a cap carried by said adapter, a pin carried by said cap and being adapted to enter one of said recesses, whereby said cap is locked against rotation, and a hinged cover for said cap and being yieldingly held in 15 closed position.
2. A device of the type described comprising an adapter having recesses therein, pins fixed on said adapter, a cap having a groove adapted to receive said pins, and a movable

pin carried by said cap and being adapted 20 to enter one of said recesses, whereby said cap is locked against rotation with respect to said adapter.

3. In a radiator-cap structure, the combination of an adapter designed to be applied 25 to a radiator-neck and having a plurality of spaced recesses disposed vertically when so applied, means to lock said adapter from turning on said radiator-neck, a cap on and adapted to turn relatively to said adapter, a pin 30 slideable in said cap and designed to drop by gravity into any registering one of said recesses to lock the cap against turning on said adapter, and means to hold said pin temporarily elevated above the level of said 35 recesses until said cap is properly positioned on said adapter.

DAVID W. BLANC.
